John McBeth, citizen of Philadelphia in

Letters Patent No. 1303-Dated May 1, 1861

Design for a Baiting

The schedule referred to in these Letters Patent and in the last of the same

contains the following

Be it known that John McBeth, citizen of the City and County of Philadelphia, State of Pennsylvania, has invented and devised a new and original design for a baiting and to hereby declare the accompanying drawing with the following explanations of the same to form a full, clear and exact description of the said design.

In the accompanying drawing the figure represents a side view of a baiting.

A A' A'' are parallel horizontal bars through all of which extend cylindrical rods a a' a'' to the lower end of each rod a' which projects below the strip A is secured a pointed ornament of the form shown in the drawing.

The upper end of each rod a is broken, and at the end of each branch of the fork is a spear head, and on each end of each rod a is a spear head.

Through the central bar is twisted a series of wires which are sharpened at each end.

John

The design for a railing substantially as shown
is set by the accompanying drawing.

As testimony whereof I have signed my name to this specification in
the presence of two subscribing witnesses.
